UNITED STATES PATENT OFFICE

PAUL TÄTZ, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

POWER SOURCE

Application filed December 29, 1927, Serial No. 243,259, and in Germany February 18, 1927.

The necessity of providing calling devices becomes more and more felt in proportion as radio frequency intelligence transmission means and methods become more popular. 5 Among the various methods adapted to effect a radio frequency call the one appears most reliable in practice in which the calling transmitters when sending out a call are modulated with a suitable alternating frequency 10 seeing that in this case the alternating frequency amplifier means provided at most receiver apparatus can be used for extending the calling range for the call.

An object of the present invention is to 15 disclose ways and means in connection with this calling method adapted to realize considerable savings in the production of the calling frequency.

Other objects of the invention will be evi- 20 dent from the following description in connection with the drawings in which

Fig. 1 represents a preferred embodiment of my invention in which the calling frequency is taken off in shunt relation, and 25

Fig. 2 shows another embodiment in which the calling frequency is taken off in series relation.

According to the idea underlying this invention, the call (modulation) frequency is 30 derived directly from the direct current service machines providing current for the filament and the plate, the calling frequency consisting of the commutation frequency (commutator ripples) of these direct current machines. The call frequency may be taken 35 from the machines, as shown in Fig. 1, either in shunt relation to the terminals of generator G, or else, as illustrated in Fig. 2, in series relation with the main service current. In this latter scheme, transformers 40 T are required which are markedly biased by the preponderant direct current component of the service current, and this is attended with difficulties. Another inconven- 45

ience is that in this circuit arrangement, the transformer must be adapted to the large service currents.

For this reason, it is recommendable to derive the call frequency in shunt across the 50 generator terminals, if possible, by way of a condenser C, Fig. 1 from the working potential.

In order to purify the call frequency, filter 55 circuits S may be used in addition.

The call frequency, generally speaking, needs to be of only limited energy since the transmitters are mostly furnished with input amplifiers and modulating means, for which reason energy being only of an order 60 of magnitude equalling the normal control energy (microphone energy) is required. Otherwise the modulation frequency may be conveniently amplified.

Having thus described my invention what 65 I desire to protect by Letters Patent is as follows:

1. In an arrangement for audio frequency modulation of radio frequency transmitters, a source of direct current for energizing said 70 transmitters said source having alternating current components, and means for utilizing the alternating current components on said direct current for modulating said transmitters.

2. A method of deriving modulating energy from existing transmitting station equipments which comprises filtering out and utilizing the commutator ripples in the existing direct current supply generators. 80

3. In a system for modulating radio frequency transmitter circuits with audio frequency energy, means for deriving said audio frequency energy comprising a circuit coupled to the direct current generators of the 85 transmitter power supply system said circuit being adapted to transfer from said generators to said modulating system any alternating current energy component present in said generator circuit. 90

4. In a system for modulating radio frequency transmitter circuits with audio frequency energy, a direct current generator for supplying said circuits with the necessary direct current potentials, means for deriving said audio frequency energy comprising a circuit having the primary winding of a transformer in series with a condenser, shunted across the generator terminals, a utilizing circuit and means comprising the secondary winding of said transformer for transferring the alternating current component from said generator to said utilizing circuit.
